STAGE CURTAIN RIGGING

Charles E. Tompkins, Syracuse, N. Y., assignor to
J. R. Clancy, Inc., Syracuse, N. Y., a corpora-
tion of New York

Application December 17, 1937, Serial No. 180,471

1 Claim. (Cl. 254—141)

My invention relates to stage curtain rigging and relates more particularly to a novel means for raising and lowering a stage curtain.

In the stage curtain riggings of the prior art adapted to raise and lower stage curtains, it has been the usual practice to counter-weight the curtain and provide sheaves over which the curtain supporting ropes are passed, and to provide a pull rope for raising and lowering the curtain. Manually operated rigging is almost universally used in theatres as it is important that the curtain be at all times under the immediate control of the operator. The type of rigging heretofore employed, in the usual installation, required a large amount of room. It was customary and necessary to provide a floor block on the level of the stage floor and a loft block high in the stage loft. Particularly, in the larger theatres which may have as many as fifty curtains, each requiring a separate rigging, the maze of curtain rigging and the large amount of room required for mounting the curtain rigging was one of the major problems in laying out a stage.

An object of my invention is to provide a stage curtain rigging which requires a minimum amount of space.

Another object of my invention is to provide a stage curtain rigging in which the sheaves and ropes are so arranged that the entire rigging may be mounted above the stage floor whereby both wings of the stage are clear and unobstructed.

My invention further contemplates the provision of a stage curtain rigging adapted to be mounted in a minimum of space and wherein the pull rope is continuous, and both in raising and lowering the curtain the same length of pull rope is required so that under no conditions of operation is there any necessity for piles of rope on the rigging floor.

More specifically, my invention contemplates the provision of a stage curtain rigging wherein the weight of the curtain is counter-balanced by a movable counter-weight and wherein a continuous pull rope is passed over sheaves, the arrangement of the curtain supporting ropes, the sheaves and the pull rope being such that the pull rope is never slack and the counter-weight in raising and lowering the curtain moves only half the distance of the curtain.

Other objects and advantages of my invention will be more apparent from the following description when taken in connection with the accompanying drawing in which:

Figure 1 is a view showing my novel stage rig-

ging and indicating the stage curtain and its supporting ropes.

Figure 2 is a view taken on the line 2—2 of Figure 1 showing the details of the counter-weight carriage and the sheave blocks mounted on the carriage.

Figure 3 is a view taken on the line 3—3 of Figure 1.

The stage curtain, indicated by the numeral 11, is supported by a plurality of curtain supporting ropes 12 which are secured to the curtain at spaced intervals along the length of the curtain. In the drawing, I have shown four supporting ropes although more or less may be used if desired, depending upon the length of the curtain. The curtain supporting ropes are passed over sheaves 13 supported in sheave blocks 14. The sheave blocks 14 may be supported in the stage loft on a common sheave block supporting member indicated by the numeral 16. 20

While I have shown only a single curtain and a single curtain rigging, it will be appreciated that on almost any stage of any size a number of curtains are used. On the most elaborate stages, the number of curtains and consequently the number of curtain riggings required may be as many as fifty.

The curtain supporting ropes 12 are each passed over a sheave 17 mounted in a sheave block 18. The sheave block 18 is supported high in the stage loft upon I-beams 19 or any other suitable manner, it being understood that the I-beams 19 support a series of loft blocks 18, one for each curtain. The curtain supporting ropes 12, after being passed over the loft sheave 17, extend downward and are passed over sheaves 21 mounted in a movable block 22. From the sheaves 21, the curtain supporting ropes 12 extend upward and are secured to the loft block 18. 30 35 40

The movable block 22 is secured, as indicated at 23, to a counter-weight carriage 24. The counter-weight carriage is slidably supported in guides which may be of any suitable type. In the drawing, I have shown the guides as being mounted on only one side of the carriage although it will be appreciated that guides may be provided on both sides of the carriage. The counter-weight carriage comprises a pair of plates 26 between which extend rods 27 upon which the counter-weights 28 are mounted. The plates 26 are retained in spaced relation on the rods by nuts 29. The counter-weights may be retained in position on the rods by clamps or collars 31 adjustably secured to the rods in any suitable manner. 45 50 55

The plates 26 are provided with down-turned flanges 32 which are bolted to slide plates 33. The slide plates are provided with grooves 34, as shown in Figure 3, in their opposite lengthwise edges 5 to receive slide guides 36 formed by the vertical edges of a pair of angle plates 37. The angle plates 37 are secured, as indicated at 38, to a bracket 39 which is rigidly secured to the wall or other fixed portion of the theatre. It will be appreciated that the guides 36 extend the required height to enable the counter-weight carriage to move upward and downward the distance required to raise and lower the curtain. Counter-weights 28 are placed in the carriage and secured there-in until the curtain is counter-balanced. Theoretically, to counter-balance the curtain, the weight of the carriage plus the weight of the sheaves mounted thereon, plus the weight of the counter-weight, should be approximately twice 10 the weight of the curtain. The curtain, as will be apparent, moves twice as fast as the counter-weight.

The stage curtains with which we are particularly concerned are quite heavy, some of them 15 weighing as much as three hundred pounds or more, and since the curtains are manually controlled, it is important that the curtain shall be substantially counter-balanced, and it is further important that the curtain shall be easy to operate in both directions. It is further important 20 that the rope used to raise and lower the curtain shall not, under certain conditions of operation, become slack so as to pile up on the floor as it will be appreciated that with a battery of fifty or more 25 curtain riggings mounted just as close together as they can be, that excess rope piled on the rigging floor causes confusion and is liable to become tangled. Accordingly, I have provided a novel arrangement of sheaves and purchase line or 30 pull rope particularly adapted to cooperate with the curtain and counter-weight system above described.

One end of the pull rope 41 is secured, as indicated at 42, to the loft block 18. From the loft 35 block 18, the pull rope extends downward and is passed over a sheave 21 mounted in the movable block 22. After being passed around the sheave 21, the pull rope 41 extends upward and is passed over a sheave 17 in the loft block 18. The 40 pull rope then extends downward and is passed over a sheave 44. The sheave 44 is mounted in a floor block 46 rigidly secured, as indicated at 47, to the rigging floor. The pull rope 41 then extends upward and is passed over a sheave 48 45 mounted in a movable block 49. The movable block 49 is secured, as indicated at 51, to the bottom of the counter-weight carriage 24. After being passed over the sheave 48, the pull rope 41 extends downward and has its end secured, as indicated at 52, to the floor block 46.

Suitable means, as indicated at 53, not necessary to be described herein since it constitutes no part of my present invention, may be provided for locking the pull rope in any desired position so that the curtain will be retained in the desired position.

It will now be apparent that with the curtain

counter-balanced, upon pulling downward on the pull rope 41, the counter-weight is raised and the curtain lowered. Upon pulling upward on the pull rope 41, the curtain is raised and the counter-weight lowered. Preferably, in setting up the 5 rigging, counter-weights are placed in the carriage until the downward pull required on the pull rope to lower the curtain is substantially the same as the upward pull required on the pull rope to raise the curtain. It will be appreciated that 10 the only pull required to raise or lower the curtain is sufficient force to overcome the friction in the system.

It will further be appreciated that the counter-weight moves only half as far as the curtain and 15 that therefore the entire rigging may be raised above the level of the stage floor and placed in a loft so that both wings of the stage are entirely clear of obstructions. It will further be appreciated that the pull rope is continuous and that 20 an upward movement of the sheave block 22 so as to shorten the length of the rope required is compensated for by an upward movement of the sheave block 49 so as to lengthen the rope required a corresponding amount. The opposite 25 occurs when the sheave block 22 is moved downward. Under all conditions, no slack and, therefore, no accumulation of rope on the floor can occur.

It will be appreciated that I have provided a 30 novel stage curtain rigging which is easy to operate and which occupies a considerably smaller space than the usual stage curtain rigging. It will further be appreciated that various changes and modifications may be made in the form and 35 relation of parts and the arrangement of sheaves without departing from the spirit of my invention as set forth in the appended claim.

I claim:

In a stage curtain rigging adapted to raise and 40 lower the curtain, a fixed loft block having sheaves around which the curtain supporting ropes are passed, a counter-weight carriage having guides in which the carriage is slidble, a block secured to said carriage and having sheaves 45 around which the curtain supporting ropes are passed from the loft block sheaves, said curtain supporting ropes having their ends secured to the loft block, and means for raising and lowering the counter-weight to lower and raise the curtain comprising a floor block having a sheave, a second block having a sheave secured to said carriage and a continuous pull rope having one end fixed in the loft block passed around a sheave in the first 50 mentioned block on said carriage, then passed upward around a sheave in the loft block, then extending downward and passed around a sheave in the floor block and then extending upward and 55 passed around a sheave in the second block on the carriage and then extending downward and secured to the floor block, and said carriage carrying counter-weights of such weight that the curtain is substantially counter-balanced so that the pull on the pull rope in raising the curtain is substantially equal to the pull on the pull rope 60 required to lower the curtain.

CHARLES E. TOMPKINS.
